UNITED STATES PATENT OFFICE.

JOHN B. LANOUE, OF TROY, NEW YORK, ASSIGNOR OF ONE-HALF TO CLARENCE H. WHITE, OF COHOES, NEW YORK.

MEDICINE-CABINET.

1,071,760.

Specification of Letters Patent.

Patented Sept. 2, 1913.

Application filed July 25, 1912. Serial No. 711,549.

To all whom it may concern:

Be it known that I, JOHN B. LANOUE, citizen of the United States, residing at Troy, in the county of Rensselaer and State of New York, have invented certain new and useful Improvements in Medicine-Cabinets, of which the following is a specification, reference being had therein to the accompanying drawing.

- 10 This invention relates to medicine cabinets, and the principal object of the invention is to provide a cabinet in which bottles of medicine may be placed and which is so constructed that all of the bottles may be exhibited without it being necessary to remove the remaining bottles from their standing places. This is accomplished by pivotally connecting a number of receptacles so that they may be swung out of the cabinet 15 thereby permitting the desired bottle to be obtained without it being necessary to remove the remaining bottles, as is necessary where the bottles are all placed in a cabinet not provided with swinging receptacles.
- 20 Another object of the invention is to so construct the receptacles that the receptacles will hold each other in a closed position and the inner receptacles be prevented from swinging out when the outer receptacles are 25 opened.
- 30 Another object of the invention is to provide a device which will hold the bottles upon the shelves of the receptacles thereby preventing any danger of their dropping 35 when the receptacles are swung outward.

In the accompanying drawings:—Figure 1 is a perspective view of the cabinet. Fig. 2 is a front elevation showing the outer compartments swung open. Fig. 3 is a view 40 similar to Fig. 2 with the inner receptacles also swung outward. Fig. 4 is a transverse sectional view with the receptacles closed. Fig. 5 is a view similar to Fig. 4 showing the outer receptacles open and indicating the 45 manner in which one of the inner receptacles holds the remaining ones closed. Fig. 6 is a view similar to Fig. 5 with one of the inner receptacles partly opened prior to opening the remaining inner receptacle. Fig. 50 7 is a vertical sectional view through the cabinet. Fig. 8 is a perspective view of one of the pivot pins which is used in mounting the inner receptacles. Fig. 9 is a sectional view showing the pivot pin in place. Fig. 55 10 is a fragmentary view showing the latch

which holds one of the outer receptacles in a closed position. Fig. 11 is a fragmentary elevation showing the construction of the device for holding the bottles in position.

This invention comprises a cabinet having 60 the enlarged lower portion 10 forming a cupboard provided with the front doors 11. This cupboard 10 may be used for any material desired, such for instance as bandages, absorbent cotton, and other materials which 65 take up a considerable amount of space. The upper portion 12 of this cupboard forms a shelf upon which bottles taken from the receptacles may be placed until the desired number of bottles have been removed 70 from the receptacles. The upper portion of the cabinet contains the bottle receptacles and comprises the rear wall 13, side walls 14, top 15 and forward receptacles 16 and 17, which as can be seen 75 form the front doors of the upper portion of the cabinet. Each of these forward receptacles is provided with the side walls 18 and 19 between which the shelves 20 are mounted. Vertical flanges 21 are at the 80 outer edges of the shelves 20 and are fitted into grooves 22 so that the outer faces of the flanges do not extend beyond the side walls. Hinges 23 connect the outer receptacles with the side walls 14 so that the 85 outer receptacles may be swung to the open position shown in Fig. 2. A bolt 24 is carried by the receptacle 16 and fits into a socket formed in the top 15 to hold the receptacle 16 in a closed position, and a lock 90 25 is carried by the receptacle 17 in order to hold the receptacle 17 in a closed position, as shown in Fig. 5. Glass windows 26 are carried by the outer receptacles so that the contents of the outer receptacles may be 95 seen through the windows, thus indicating that the cabinet is a medicine cabinet.

The inner receptacles 27 and 28 are pivotally mounted between the shelf 12 and top 15 by means of pivot pins 29 which are 100 secured to the inner receptacles as shown in Fig. 2. The pivot pins are reduced and pass through bearings 31 which form the sockets to prevent the platform 12 and top 15 from being worn to such an extent that the inner 105 receptacles would not work properly. Each of these inner receptacles is divided into two sections by means of the vertically extending partition 32 having its edge portions positioned in grooves formed in the side walls 110

of the inner receptacles. Shelves 33 similar to the shelves 20 are mounted to each side of the partition 32 and are provided with flanges 34 at their outer edges which are positioned in grooves similar to the manner in which the flanges 21 are mounted. From inspection of Figs. 4, 5, and 6, it will be seen that the end walls 35 and 36 of the receptacles 27 and 28 respectively are wedge shape in cross section, the wall 36 being provided with a curved face. By this construction the receptacle 28 may be swung outwardly as indicated in Fig. 6, the curvature of the wall permitting the receptacle to be swung outwardly without coming into contact with the wall 35. If, however, as shown in Fig. 5 the receptacle 27 attempts to move out before the receptacle 28 has been opened its inner end portion will come in contact with the thickened wall 36 thereby stopping the movement of the receptacle 27 and prevent its being opened beyond a certain amount. It will thus be seen that after the receptacles 27 and 28 have been swung inwardly and the receptacle 28 locked by means of the locking pin 37 that the two inner receptacles will be securely held in a closed position. It will also be seen that even if this pin 37 were omitted that the outer receptacles would hold the inner receptacles in place when closed, since the inner edges of their walls 19 come in contact with the walls 35 and 36 as clearly shown in Fig. 4, thereby holding these receptacles in a closed position.

Shelves 38 are mounted in the rear portion of the cabinet between the side walls 14 and the rear wall 13. These shelves 38 are also provided with the flanges 39 at their forward edges which prevent the bottles from slipping from the shelves when the outer and inner receptacles are opened. In order to assist these flanges carried by the shelves in preventing the bottles from being knocked from the shelves there has been provided a resilient device which is clearly illustrated in Fig. 11. This device comprises a resilient wire 40 which has one end connected with the pin 41 in one of the grooves at one end of each of the flanges for shelves. A spring 42 has one end connected with a pin 43 mounted in the groove at the opposite end of the shelf, and the inner end of the wire 40 is connected with the inner end of the spring 42 so that the wire 40 will at all times be held under a tension. When placing a bottle upon one of

the shelves the bottle is forced back of the wire and will be held firmly in place, since it will require a little effort to remove the 60 bottle.

When using this device the bottles are placed upon the shelves behind the wires and the inner receptacles 27 and 28 are first closed, the receptacle 27 being closed before 65 the receptacle 28 and the outer receptacle 18 are then swung to the closed position and locked. When desired to obtain one of the bottles the outer receptacles are swung open and if the desired bottle is not on one of the 70 shelves of the outer receptacles the inner receptacles can then be swung open and the contents of the entire cabinet will be exposed to view, thereby making it very easy to select the desired bottle. The cabinet can 75 be then again closed and the several compartments will hold each other in a closed position.

Having thus described the invention what is claimed as new, is:—

1. A cabinet comprising a body portion, inner receptacles pivotally mounted between the side walls of said body portion, the inner walls of said receptacles being thickened to form oppositely inclined wedge shape 85 walls to cause one of said receptacles to prevent the opening of the other of said receptacles when said receptacles are in a closed position, the wall of said first mentioned receptacle being curved to permit the receptacle to be swung open, means for holding said first mentioned receptacle in a closed position, and doors for said cabinet closing in upon said inner receptacles.

2. A cabinet comprising a body portion, 95 receptacles pivotally mounted in said body portion, pivot pins at the upper and lower ends of said receptacles and provided with reduced free end portions passing through bearings carried by the top and bottom of 100 said cabinet, the inner end walls of said receptacles being thickened and wedge shape in cross section whereby one of said receptacles will hold the other of said receptacles in a closed position, and doors for said cabinet 105 engaging said receptacles when in a closed position to hold the receptacles stationary.

In testimony whereof I hereunto affix my signature in presence of two witnesses.

JOHN B. LANOUÉ.
